UNITED STATES PATENT OFFICE

JAMES F. MCINTIRE, OF DETROIT, MICHIGAN, ASSIGNOR TO UNITED STATES RADIATOR CORPORATION, OF DETROIT, MICHIGAN, A CORPORATION OF MICHIGAN

DESIGN FOR A RADIATOR

Application filed August 3, 1931. Serial No. 40,762. Term of patent 14 years.

To all whom it may concern:

Be it known that I, JAMES F. MCINTIRE, a citizen of the United States of America, residing at Detroit, in the county of Wayne and State of Michigan, have invented a certain new, original, and ornamental Design for a Radiator, of which the following is a specification, reference being had therein to the accompanying drawings, forming a part thereof, wherein:

Figure 1 is a perspective view of a radiator showing my new design, and

Figure 2 is a top plan view thereof.

The dominant feature of my design consists in forming the body portion of the radiator of one or more thin sections, each section being substantially the length and height of the radiator and each section being surrounded by a plurality of outstanding spaced ribs, these ribs being relatively thin and of substantial depth.

I claim:

The ornamental design for a radiator substantially as shown and described.

JAMES F. MCINTIRE.
